UNITED STATES PATENT OFFICE.

HOLLING G. TUCKER, OF HEREFORD, TEXAS, ASSIGNOR OF ONE-HALF TO
CLAUDE S. GASS, OF HEREFORD, TEXAS.

OVEN FOR OIL-BURNERS.

SPECIFICATION forming part of Letters Patent No. 744,945, dated November 24, 1903.

Application filed August 27, 1902. Serial No. 121,256. (No model.)

To all whom it may concern:

Be it known that I, HOLLING G. TUCKER, a citizen of the United States, residing at Hereford, in the county of Deaf Smith and State 5 of Texas, have invented a new and useful Oven for Oil-Burners, of which the following is a specification.

This invention relates to ovens for oil-burning stoves; and it has for its object to provide 10 an oven especially suitable to be used in connection with what is known as "crude-oil" burners, more particularly of the form shown and illustrated in Letters Patent of the United States granted to me on July 15, 1902, and 15 numbered 704,669.

The improved oven, which is the subject of my present invention, is provided with interiorly-arranged flue-plates forming passages through which the air heated by the burner 20 may be permitted to pass directly in contact with the casing constituting the oven proper or with an interior casing, or with both, thus enabling the oven to be heated to any desired degree, dampers being arranged so as to perfectly regulate the passage of the hot air. 25

The invention further consists in the improved arrangement and construction of an overflow-basin which when weighted down by the overflow from the burner will automatically 30 shut off the fuel-supply, thereby avoiding all danger of accident resulting from an oversupply of the fuel-oil.

With these and other ends in view the invention consists in the improved construction, arrangement, and combination of parts, 35 which will be hereinafter fully described, and particularly pointed out in the claims.

In the accompanying drawings, Figure 1 is a view, partly in section and partly in elevation, of a device constructed in accordance 40 with my invention. Fig. 2 is a vertical sectional view taken through the oven part of the device on the line 2 2 in Fig. 1.

Corresponding parts in both figures are indicated by similar numerals of reference.

1 designates the oven, which consists of a rectangular box or casing comprising the sides 2 2, back plate 3, top plate 4, bottom plate 5, and the door 6.

50 7 designates a hopper-shaped casing, the front and rear edges of which are connected

with the front and rear edges of the bottom plate 5 of the oven, while the ends 8 8 of said hopper are extended beyond the end plates 2 2 of the oven and have upward extensions 9 9, the upper edges of which are connected by a top plate 10, with which they coöperate to form the exterior casing of the oven. The back plate 3 of the oven is extended laterally, as at 11, and upwardly, as at 12, to meet the rear edges of the plates 9 and 10. The front edges of the side plates 2 and 9 and 4 and 10 are likewise connected by plates, (designated, respectively, 13 and 14,) thus forming a complete space inclosing the three sides of the oven, as will be clearly seen by reference to the drawings.

In the vertical side spaces 11 are disposed vertical flue-plates 15, which are supported between the front plates 13 and the extensions 70 of the back plate 2, thus forming flues 16 and 17, which are disposed, respectively, between the flue-plates and the oven-casing proper and between said flue-plates and the exterior casing. Dampers 18 and 19 are disposed at 75 the lower ends of the flues 16 and 17, so as to regulate the passage of the heated air therethrough.

The top plate 10 of the exterior casing is provided with suitable openings 20 for the escape of air.

The hopper-shaped casing 7, which extends downwardly from the exterior casing of the oven, is provided at its lower end with a cylindrical sleeve 21, through which extends 85 the fuel-pipe 22, supporting the burner 23. This burner, as already stated, has been patented to myself and does not require to be described in detail. The sleeve 21 is provided with draft-openings 24, and it has at its lower 90 edge an inwardly and upwardly extending flange or collar 25, in which is slidingly mounted a basin 26, which is of circular shape, so as to fit nicely within the flange or collar, in which it has a vertically-sliding movement. 95 This cup is designed to receive the drippings and overflow from the burner, which is disposed directly above.

The supply-pipe 22 extends upwardly through a suitable support 27 and is provided 100 with a valve 28, through which the liquid fuel is admitted to the burner. This valve is pro-

vided with a crank arm or handle 29, which is connected, by means of a spring 30, with a post or upright 31, having a stop 32, which is so disposed that when the arm 29 is held in engagement therewith by the tension of the spring 30 the valve shall be closed. To open the valve, it is drawn downward against the tension of the spring and is engaged with a trigger 33, mounted pivotally at the upper end of an upright 34 and having a beveled end 35 to permit the arm 29 to be readily passed by and placed in engagement therewith. Another upright 36, mounted upon the support 27, carries a lever 37, one end of which has loose pivotal connection with the trigger 33, while its opposite end supports the vertically-sliding cup or overflow-basin 26, which may rest upon a block 38, so as to distribute its weight evenly upon the end of the lever.

The operation of this invention will be readily understood from the foregoing description taken in connection with the drawings hereto annexed. While the device is in use the arm or lever 29 is normally in the position indicated by Fig. 1—that is, engaging the trigger 33, whereby the valve 28 is kept open and the fuel-oil permitted to enter the burner. The overflow from the latter enters the cup or basin 26, which rests, as described, upon the outer end of the lever 37. At a predetermined point the latter is overbalanced, thus raising the inner end of the trigger and disengaging the arm 29, which is instantly under the influence of the coiled spring 30, drawn to the position indicated in dotted lines, resting against the stop 32, when the valve will be closed. The cup or basin 26 may then be removed, emptied of its contents, and restored to operative position. The said cup or basin being supported by the flange 25 at a distance from the inner wall of the sleeve 21 leaves an annular air-space which materially assists the draft. The air heated by contact with the flame will ascend through the flues surrounding the oven-casing, and the passage through said flues may be so regulated by the dampers 18 and 19 as to subject the said oven-casing to a greater or less degree of heat, as will be very readily understood. Thus by opening the outer dampers 19 and closing the inner ones the hot air will pass through the outer flues and the oven will be comparatively lightly heated. By opening one of the outer and closing one of the inner flues on either side the draft may be regulated in an obvious manner, while by

permitting the hot air to ascend only through the inner flues and closing the other ones the oven-casing will be subjected to the greater available degree of heat.

I have in the foregoing described what I consider to be the preferred form of my invention; but I desire it to be understood that I do not limit myself with regard to the structural details of the same, but reserve the right to any changes, alterations, and modifications which may be resorted to without detracting from the utility of my invention or departing from the spirit and scope thereof. Thus, for instance, it is evident that the front of the oven-casing proper is to be provided with a door, as shown in the sectional view Fig. 2, the ends of the damper-rods are to be provided with handles by means of which they may be conveniently manipulated, the front side of the hopper 7 is provided with an opening through which the burner may be reached for the purpose of conveniently igniting the flame, and the oven with its related parts is to be supported upon suitable framework.

Having thus described my invention, I claim and desire to secure by Letters Patent of the United States—

1. An oven comprising an inner casing, an exterior casing surrounding the ends and top of the inner casing and forming within said exterior casing end spaces which are open at their upper and lower ends, vertical flue-plates disposed in the end spaces and spaced from the inner and outer casings, and dampers independently controlling the passage of air through the flues thus formed.

2. An oven comprising an inner casing, an exterior casing surrounding the ends and top of the inner casing, and forming within said exterior casing end spaces which are open at their upper and lower ends, flue-plates disposed vertically in the end spaces thus formed, dampers independently controlling the passage of air and products of combustion through the flues between the flue-plates and the inner and outer casings, a hopper depending from the lower edges of the exterior casing, and a burner disposed in said hopper.

In testimony that I claim the foregoing as my own I have hereto affixed my signature in the presence of two witnesses.

HOLLING G. TUCKER.
